UNITED STATES PATENT OFFICE.

WILLIAM FONDILLER, OF NEW YORK, N. Y., ASSIGNOR TO WESTERN ELECTRIC COMPANY, INCORPORATED, OF NEW YORK, N. Y., A CORPORATION OF NEW YORK.

LOADING SYSTEM.

Application filed May 8, 1923, Serial No. 637,474. Renewed October 2, 1924.

This invention relates to loading systems and more particularly relates to an arrangement for loading signaling lines such as telephone or telegraph cables.

- 5 An object of this invention is to provide an efficient loading system for signal conductors such as underground or aerial toll cables, particularly for signaling currents in the ultra audio frequency range.
- 10 The form of this invention hereinafter described in detail is employed with particular advantage for loading toll cables for the so-called carrier frequency range whereby efficient transmission may take place
- 15 along the cable for ultra audio frequencies.

Commercial lumped loading of the Pupin type is, as is well known in the art, the equivalent of a low pass wave filter which gives free transmission for all frequencies below a definite cut-off frequency, f_c , given by the equation,

$$f_c = \frac{1}{\pi\sqrt{LC}}$$

- 25 Since for lumped loading of the Pupin type the distance between coils must be decreased to secure an increase in the upper limiting range to be transmitted, or otherwise smaller inductances must be used with a resulting high attenuation, such a large number of loading coils is required to load the cable for carrier frequencies as compared to the number required for speech frequency transmission that the cost is almost prohibitive, even taking into account the extra signaling channels obtained by the raising of the upper limiting frequency. The relatively large amount of space required by loading coils is highly objectionable in many cases, as in underground cables where the loading coils are placed in manholes and the space available is limited and costly. On the other hand continuous loading of the conductors by an individual wrapping of magnetic material is also open to objection because of the high cost due to increased size of cable, increased duct space, shipping weight, etc. The overall size of a cable is furthermore limited by various economical and manufacturing conditions so that if each quad must be continuously loaded the extra space required will reduce considerably the number of quads that may be placed in the standard

size of cable. The loading arrangement proposed for this invention is a compromise between continuous and lumped loading whereby the objections to each of these methods are minimized to a substantial degree.

Instead of having each conductor of the cable continuously loaded along its entire length, it is proposed to apply the continuous loading to only a fractional part of the conductors in each section of the cable, the continuously loaded conductors of one section being so connected to non-loaded conductors of the adjacent sections that the loaded sections are uniformly distributed along each signaling path and are joined by the same lengths of non-loaded conductors. For example, one-half of the total number of conductors in one section of the cable may be continuously loaded, while the remaining half are non-loaded. In splicing a cable a continuously loaded quad would then be connected to a non-loaded quad in the succeeding section and so on. An obvious extension of this would be to load only one-third or one-fourth of the quads in each section so that the loaded quad of one section would be connected to a non-loaded quad in the next two or three sections, as the case may be.

An embodiment of this invention is disclosed in the accompanying drawing.

Referring in detail to the drawing, a portion of a telephone cable is disclosed, divided for convenience, into three sections, designated A, B, and C. Each of these sections is shown to comprise only four quads, although in commercial practice a telephone toll cable comprises a much larger number of quads, and consequently of conductors. In order to obtain satisfactory transmission through the cable, particularly for carrier frequencies up to 30,000 cycles, 50,000 cycles, or more, it is proposed to apply continuous loading to one-half of the quads or conductors in each section of the cable, the loaded quads or conductors in one section being connected to non-loaded quads or conductors in the succeeding section, and so on, so that the continuously loaded sections of any transmission line through the cable will occur at constant intervals. This will, of course, result in a compromise between continuous loading along the entire length of

each conductor and lumped loading wherein loading coils are spaced at uniform distances along the transmission lines.

In section A of the cable, the pairs of conductors 5, 6, 7 and 8 are shown to be continuously loaded by a suitable wrapping of a proper magnetic material composed, for example, of iron-nickel alloy, while the pairs 9, 10, 11 and 12 are non-loaded. Similarly, 10 pairs 13 to 16 of section B and pairs 21 to 24 of section C are continuously loaded, while pairs 17 to 20 of section B and pairs 25 to 28 of section C are non-loaded. The loaded quads 5, 6 and 7, 8 of section A are connected 15 to the non-loaded quads 17, 18 and 19, 20 of section B and then to the loaded quads 21, 22, and 23, 24 of section C. Similarly, the non-loaded quads 9, 10 and 11, 12 of section A are connected to the loaded quads 13, 14 and 15, 16 of section B and then to the non-loaded quads 25, 26, and 27, 28 of section C, so that for any one particular transmission line the loaded sections and the non-loaded sections are alternated.

25 The material employed in obtaining the continuous loading is not a part of this invention, since any suitable material may be employed having the proper permeability and a sufficiently high specific resistance.

30 The arrangement of this invention clearly minimizes one of the principal objections to continuously loaded cables, that is, high cost due to increased size of the cable, increased duct space, shipping weight, etc., and is also particularly adapted to the most modern type of phantom circuits. It is also believed to be more economical than coil loading spaced at sufficiently short intervals to give a cutoff frequency above the carrier range. 35 Furthermore, the cutoff frequency obtained with the continuous loading of this invention is unusually high compared with the cutoff frequency obtained with lumped coil loading having the same inductance per mile.

40 In carrier current loading systems, present practice is to place a loading coil in the line of 4.83 M. H. every 930 feet when, for example, the total capacity per section of the line is .0122 m. f. Under these conditions the attenuation is low and uniform for all frequencies up to the so-called "cut-off" frequency which in the above case would be 41,500 cycles.

45 In accordance with the plan of this invention however, each 930 foot section would be composed of equal lengths of continuously loaded and non-loaded conductors. The capacity per section would then be only one half that in the lumped loaded case or .0061 m. f. This with the same amount of loading per section, namely 4.83 m. h. per section gives a cutoff frequency of 50,000 cycles. The total loop inductance is the same in both cases but the cutoff frequency is somewhat higher when the loading is in accord-

ance with this invention, thus permitting carrier operation at even higher frequencies than with standard loading of the same inductance per section.

An obvious extension of the arrangement 70 shown in the drawing is to apply continuous loading to only one-third or one-fourth of the quads in each section, so that the loaded quad of one section would be connected to a non-loaded quad in the next two or three sections, as the case may be. Another form this invention may take is to load all the quads in a plurality of sections of the cable and to connect them by one or more interposed sections of cable composed entirely of non-load- 75 quads.

80 Other modifications of the arrangement disclosed may also be made without departing in anywise from the spirit of this invention, as defined in the appended claims. 85

The invention claimed is:

1. A transmission line comprising a pair of line conductors arranged in alternately recurring continuously loaded and non-loaded sections, each loaded section comprising a 90 pair of line conductors and means for continuously loading said conductors throughout the section, said loaded sections being substantially uniformly spaced along said line. 95

2. A signaling cable, comprising a plurality of quads divided along their length into a plurality of arbitrary sections, each of the sections of said cable comprising a plurality of continuously loaded quads, and a plurality of non-loaded quads, each loaded quad in each section being connected to a non-loaded quad in a sufficient number of adjacent sections to distribute uniformly the loaded quads between the non-loaded quads 100 for each resulting signaling path. 105

3. A carrier frequency toll cable comprising a plurality of sections spliced together, each section comprising a plurality of quadded conductors, one-half of said quads being continuously loaded, the remaining half of said quads being non-loaded, each loaded quad in each section being connected to a non-loaded quad in the two adjacent sections. 110

4. A signaling system comprising a plurality of signaling conductors divided into a plurality of sections, certain of said sections comprising conductors continuously loaded by a wrapping of magnetic material, a plurality of said sections comprising non-loaded conductors, the loaded conductors being connected to non-loaded conductors in adjacent sections to uniformly space the loaded portions along each signaling path 115 formed thereby. 120

5. A loaded line comprising alternately recurring continuously loaded and non-loaded sections, each loaded section comprising a line conductor and means for continuously 130

loading said conductor throughout the section, said loaded sections being substantially uniformly spaced along said line.

6. A loaded signaling line comprising a plurality of non-loaded sections and a plurality of continuously loaded sections, each of said loaded sections comprising a line conductor and means for continuously loading said conductor, the non-loaded sections being connected to the loaded sections to substantially uniformly space the loaded sections along the line.

7. A loaded signaling line comprising a plurality of non-loaded sections and a plurality of continuously loaded sections, each of said loaded sections comprising a line conductor and a layer of magnetic material surrounding said conductor, the non-loaded sections being connected to the loaded sections to substantially uniformly space the loaded sections along the line.

8. A signaling system comprising a plurality of loaded conductors employing a plurality of sections, certain of said sections comprising conductors continuously loaded by being surrounded by a layer of magnetic material, a plurality of said sections comprising non-loaded conductors, the loaded conductors being connected to the non-loaded conductors in adjacent sections to substan-

tially uniformly space the loaded sections along each signaling path formed thereby.

9. A signaling system comprising a plurality of signaling conductors which may be considered divided into a plurality of sections, a plurality of the conductors in each of said sections being non-loaded, means associated with a second plurality of conductors in each of said sections whereby said second plurality of conductors are continuously loaded, said sections being so connected that a loaded conductor in one section is connected to a non-loaded conductor in other sections to substantially uniformly space the loaded sections along each signaling path.

10. In a transmission system a group of line conductor pairs divided into sections at the same points along their lengths, certain conductor pairs in the section between two given points of division being non-loaded and certain of the pairs in the same section being continuously loaded, similarly loaded conductor pairs and non-loaded pairs in the successive sections, the loaded conductor pairs of each section being connected to non-loaded conductor pairs of adjacent sections to form continuous transmission paths.

In witness whereof, I hereunto subscribe my name this 2nd day of May, A. D. 1923.

WILLIAM FONDILLER.
